ATTORNEY

UNITED STATES PATENT OFFICE.

HENRY L. GUENTHER, OF LOS ANGELES, CALIFORNIA.

DIFFERENTIAL-SPEED CAN-FEED MECHANISM.

Application filed December 21, 1921. Serial No. 523,826.

To all whom it may concern:

Be it known that I, HENRY L. GUENTHER, a citizen of the United States, residing at Los Angeles, in the county of Los Angeles and State of California, have invented new and useful Improvements in Differential-Speed Can-Feed Mechanism, of which the following is a specification.

This invention relates to a can feeding device and particularly pertains to a differential can feeding mechanism.

It is the principal object of the present invention to provide means for feeding can bodies and can caps co-incidently to a double seaming machine, the can bodies being filled with fruit, vegetables or other material. It has been found in practice that high speed of double seaming machines have been prohibitive due to the fact that the cans were fed to them while their rate of speed in travel was rapidly increased as they entered the machine. It has been the principal object of this invention, therefore, to increase the speed of the cans gradually and thus to deliver the cans to the machine after it has gradually increased in speed to the rate of travel it will assume while passing through the seaming machine.

The present invention contemplates the use of a constantly operated, slow speed mechanism, and a high speeding mechanism to which the cans are subsequently delivered; interposed between said mechanisms being a differential speed feeding device which increases the speed of the cans from that at which they are being fed along the first device to the speed of the last named feeding device.

The invention is illustrated by way of example in the accompanying drawings, in which:

Figure 1 is a view in plan disclosing the complete feed mechanism with which the present invention is concerned.

Fig. 2 is a view in vertical section through the feed device showing the general arrangement and driving construction of the parts.

Referring more particularly to the drawings, 10 indicates the main body of a double seaming machine. Secured to this member and near the bottom thereof is a bearing frame 11, while secured in horizontal spaced relation above this frame is an upper bearing frame 12. The lower frame carries suitable vertical bearings for the shafts of the

mechanism, which bearings are complementary to similar bearings embodied within the upper frame member. At the extreme outer end of the frame member a vertical feed shaft 13 is rotatably secured. This shaft is designed to operate a lever arm 14 secured to its upper end, which arm is pivotally connected to a pitman rod 15. The pitman rod 15 is secured to a cross head 16 of a can cap feeding mechanism. This mechanism comprises a pair of parallel feed bars 17 which normally support a stack of can caps 18 and are so formed as to cut the lower-most can cap from the stack when the bars are alternately reciprocated.

A pusher bar 19 is also secured to the cross head and acts to push the lower-most can cap from the stack. These members slide between a top plate 20 and a floor plate 21. It will be understood that the floor plate is above the normal top of the cans which pass through the machine and that the can caps will be successively dropped from the stack to be engaged by mechanism which will carry them through the machine with the can bodies. The can caps are fed to be delivered directly above guide rails 22 and 23. These rails are concentric to a shaft 24 around which a plurality of differentially operating feed members rotate and which mechanism will be hereinafter described. The rails 22 and 23 tend to guide can bodies 25 from the initial slow speed mechanism to the high speed mechanism at the opposite end of the can track.

The slow speed device comprises a horizontally disposed rotary disc 26 which is mounted upon a shaft 27. This disc lies substantially flush with the upper face of a base plate 28. It is common practice to provide a disc upon which the cans rest and by which they are frictionally engaged, in the present instance, however, positive feeding means have been provided as a part of the disc. These comprise vertically moving fingers 29, which fingers may project upwardly through slots 30 in the faces of the discs. The slots are radially disposed and are spaced equidistant from each other around the circumference of the disc. The feed fingers 29 are carried by pivoted arms 31. The arms are secured to lugs formed as part of the disc projecting downwardly therefrom. The arms and fingers will normally fall away from the disc and the upper ends of the fingers will lie flush with the upper face

of the disc until such a time as the arms strike a lifting cam 32. This cam will swing the arms upwardly and project the fingers through the openings 30 of the disc. The arms will then swing in behind the forwardly moving cans and will positively feed them. This is particularly necessary due to the fact that a gradual increase of speed of the cans is imparted to them as they travel along the disc due to the provision of eccentric guide tracks 33 and 34. The eccentric track members 33 and 34 are arranged eccentric to the shaft 27 and will gradually crowd the cans outwardly toward the edge 15 of the feed disc 26. This will cause them to more rapidly travel as they pass from the ends of the track members 33 and 34 and into engagement with the differential feeding arms 35.

Another positive means of feeding the cans forwardly as the disc 26 rotates comprises a central hub 36 carrying a plurality of yieldably radial arms 37. These arms are held in their outer-most positions by expansion 20 springs 38 and act to positively feed the cans while moving out of the way when a can is fed onto the disc and out of synchronism with the feeding mechanism.

The arms 35 are separately pivoted to the vertical shaft 24. These arms are intended to have independent movement relative to each other. This movement is brought about by a sprocket chain 39 which passes around a sprocket 40 carried upon a shaft 24. The chain also travels around an eccentric guide member 41 which causes the chain to travel in an eccentric path of travel around the shaft 24 and the speed of the cans will be accelerated as will be readily understood. Each of the arms 35 is formed with radial slide-ways 42 which receive sliding blocks 43. Each of the sliding blocks is fitted with a pin 44 carried by the sprocket chain. By reference to Fig. 1 it will thus be noted that as the arms are driven and caused to swing around the shaft 24 by the driving action of the chain the blocks will swing in and out and will exercise different leverages upon the arms to cause them to not only swing 40 around the shaft 24 but to have an independent swinging movement relative to each other. Thus it will be seen that the arms are close together on the right hand side of the shaft 24 and are farther apart on the opposite side. This is due to the fact that the speed of the arms increases from right to left and the cans thus delivered to a final feeding spider 45 at a much greater speed of travel than when received by the arms 50 as delivered from the first feed disc 26.

It will be understood that each of the arms are formed with semi-circular recesses 46 into which the can bodies seat, said recesses carrying can cap feed blades 47' for 55 engaging the lower-most can cap fed from

the stack 18 and for carrying this cap between the track members 23 and 24 and therealong.

The driving mechanism of the present invention comprises a main spur gear 47 which 70 may be driven from any suitable source of power and which is keyed to the shaft 24. This gear is in mesh with an intermediate gear 48 which drives a gear 49. The gear 49 is carried upon a spur shaft 50 carrying a gear 51. This gear is in mesh with a large gear 52 secured to the shaft 27 and driving the disc 26. The gear 49 is also in mesh with a gear 53 secured to the lower end of the can cap feed shaft 13.

With reference to Fig. 2 it will be seen that a housing 54 is formed in the supporting frame structure 12 and through which shaft 24 extends. A supporting member 55 is disposed in this housing and circumscribes the shaft. This member serves as a guide for the chain and carries the eccentric guide portion 41 previously described.

In operation of the present invention, cans are fed from a suitable supply to the feed disc 26. At this point they are deposited on the horizontal disc which is rotated in the direction of the arrow "A." As the disc moves forwardly with the cans the fingers 29 will be projected upwardly when their lever arms strike the track cam 32 and elevates them. The cans will then pass along between the guide tracks 33 and 34 gradually moving outwardly towards the edge of the disc 26 and thereafter coming into register with the recess 46 of one of the differential feed arms 35. At this point the can will pass between the feed arm and the outer guide track member 22. The feed arms will at this time be moving at their slowest rate of speed due to the increased lever arm action of the chain and the slide blocks. As the arms proceed to be driven around the shaft 24 the slide blocks will gradually move ahead shortening the leverage and increasing the speed of travel of the arm. This will act to whip the arm around and gradually increase its speed. At a point intermediate the point of receiving the can body and discharging the same, a can cap is fed from the stack 18. This is engaged by the upstanding blade 47' carried by the arm and will be then carried along the track members 22 and 23 to the point of discharge of the can from the arm and to the spider 45. It will be understood that the shaft 13 has been operating in synchronism with the other shafts and that the feed bars 17 and the bar 19 will be alternately reciprocated to successively feed the can caps onto the tracks 22 and 23 and into engagement by the blade 47' of the various arms 35.

It will thus be seen that the present invention embodies a very compact and mechanical arrangement whereby cans and their caps

may be co-incidently fed from a source of supply to a can seaming machine at a gradually increased rate of speed and by a movement which is entirely positive.

5 While I have shown the preferred form of my invention, as now known to me, it will be understood that various changes in the construction, combination and arrangement of parts may be made by those skilled in the 10 art without departing from the spirit of the invention as claimed.

Having thus described my invention, what I claim and desire to secure by Letters Patent is:

15 1. In a can capping machine, a can feed device comprising a feed disc, onto which a flow of cans are delivered, an accelerating feed device interposed between said disc and the can-capping machine, whereby the cans 20 received from the disc will be successively fed to the can capping machine at a gradually accelerating speed of travel, a second differential accelerating means in conjunction with said disc for gradually accelerating 25 the rate of travel of the cans as they are delivered to the second feed means, intermittently operated positive means for feeding the cans forwardly with the disc, and yieldable means for disposing the cans in 30 register with the positive feed means of the disc.

2. In a can capping machine, a can feed device comprising a rotary disk onto which a flow of cans is delivered, an eccentric track 35 disposed above said disk and along which the cans are fed by a uniform rotation of the disk, positive means adapted to be automatically disposed in the rear of each of the cans delivered to the disk and by which the 40 cans will be positively fed along the track, and a plurality of can feed arms swinging around a common axis and adapted to re-

ceive the cans fed along the track and being independently movable and means interposed between said device and the arms 45 whereby they will be caused to swing around their axis at a differential speed.

3. In a can capping machine, a can feed device, comprising a rotary disk onto which a flow of cans is delivered, an eccentric track 50 disposed above said disks and along which the cans are fed by a uniform rotation of the disk, positive means adapted to be automatically disposed in the rear of each of the cans delivered to the disk and by which the cans will be positively fed along the track and a plurality of can feed arms separately pivoted swinging around a common axis and adapted to receive the cans fed along the track and means interposed between said device and the arms whereby they will be caused to swing around their axis at a differential speed.

4. In a can capping machine, a can feed device comprising a feed disc, means for 65 driving said disc at a constant rate of speed, vertically moving feed means adapted to be projected through the disc to positively engage the cans delivered to the disc, and radially slid able spring actuated fingers adapted to engage the cans and arrange them to travel forwardly with the disc at predetermined intervals.

5. In a can feed mechanism an accelerating feed device comprising a plurality of 75 radial arms adapted to travel around a common center and to receive cans at their outer ends, a driving device therefor, operating at a constant speed, and means interposed between said device and the arms, whereby 80 they will be caused to swing around their axis at a differential speed.

HENRY L. GUENTHER.
